CLAIM

[**] Term: 14 Years

The ornamental design for a lockable ski-holder, as
shown and described.

[21] Appl. No.: 837,983

DESCRIPTION

[22] Filed: Feb. 19, 1992

FIG. 1 is a perspective view of the top, side and one end
of a lockable ski-holder showing my new design; and,
FIG. 2 is a perspective view of the bottom, side and
opposite end thereof.
